Harold E. Stonebreaker,
his ATTORNEY

UNITED STATES PATENT OFFICE.

LEON D. SLADE, OF ROCHESTER, NEW YORK, ASSIGNOR TO GLEASON WORKS, OF ROCHESTER, NEW YORK, A CORPORATION OF NEW YORK.

FURNACE.

Application filed April 5, 1922. Serial No. 549,700.

To all whom it may concern:

Be it known that I, LEON D. SLADE, a citizen of the United States of America, residing at Rochester, in the county of Monroe and State of New York, have invented certain new and useful Improvements in Furnaces, of which the following is a specification.

My invention relates to furnaces of the general type in which articles to be treated are fed through from one end to the other during a heat hardening, annealing, or other heat treating process, and it has for its purpose to afford a practical and efficient support or feeding mechanism for the articles during the heat treatment.

More particularly, the invention has for its object to provide a conveyor in the form of rotating rolls, and so constructed as to successfully withstand high temperatures of from 1000° to 1900° Fahrenheit such as are present in electric heat treating furnaces.

A further purpose of the invention is to afford roll feeding mechanism capable of supporting and carrying relatively small articles, and which can be subjected to temperatures of any desired degree without damaging or seriously affecting the feeding rolls, and further in providing for the replacement of any one of the feeding rolls independently of the others.

To these ends, the invention comprises the arrangement set forth in the following specification, which will be clearly understood in conjunction with the accompanying drawing, the novel features being pointed out in the claims following the description.

In the drawing:

Figure 1 is a transverse vertical sectional view illustrating a practical embodiment of the invention;

Figure 2 is a side elevation with parts broken away, and

Figure 3 is a longitudinal vertical sectional view with parts broken away.

In the construction illustrated, A designates a heating chamber preferably of reduced width at the bottom to afford a runway B, while C designates electrical heating elements disposed at the upper or wider portion of the heating chamber and between the sides thereof and the sides of the runway B. This arrangement protects the

heating elements and prevents their being broken or struck by the articles under treatment as they travel through the furnace in the runway B, although the heating elements may be located at the top of the furnace or otherwise positioned out of the path of the articles traveling through.

The articles under treatment are fed through the chamber by a conveyor comprising a series of rolls D, arranged horizontally in the runway B and preferably slightly above the bottom thereof. The rolls D are of relatively small diameter, ordinarily about an inch and a half, and arranged in relatively close relation to each other, ordinarily at a distance of about two inches between the rolls, so as to make it possible to support relatively small articles, and carry them through the furnace without the possibility of their falling between the feeding rolls.

To accomplish this result, I preferably employ solid rolls, made from a metal that will withstand the maximum working heat of a furnace without buckling, becoming distorted, or wasting away, so as to require frequent renewal. One metal which has been found satisfactory for this purpose is thermalloy, a composition containing approximately 80% iron and 20% chromium. Other metals which can be used successfully for making the rolls are chromel, containing approximately 75% nickel and 25% chromium, nichrome, containing approximately 60% nickel, 20% chromium and 20% iron, or any alloys of chromium or nickel. With an alloy such as above mentioned, the rolls D can be made of very small diameter, and will maintain their original form and condition under temperatures up to about 1900° F. Thus, the entire heating chamber can be maintained at a uniform temperature, and there are no heat losses due to having to cool or protect the feeding rolls.

The rolls are of substantially the same diameter, and each roll is preferably of uniform diameter throughout its length, to facilitate removing any particular roll independently of the others, they being removable endwise from the furnace. The rolls may be driven by any suitable mechanism, and in the embodiment shown, each roll carries at its outer end a worm gear E located

outside the furnace, and engaged by a worm F extending longitudinally and cooperating with the worm gears E on the several rolls.

The term "heat resisting," as used throughout the claims of this application, is intended to refer to the permanent character of the rolls, or the quality which permits their being exposed to high temperatures without becoming distorted, wasting away, or otherwise changing their original form.

The invention is not limited to electric furnaces, or to the precise arrangement set forth in the present disclosure, and this application is intended to cover any modifications or departures involving the utilization of feeding rolls made of heat resisting material, or coming within the terms of the following claims.

I claim:

1. In a furnace adapted for working temperatures of approximately 1000° to 1900° F., the combination with a heating chamber, of a conveyor comprising a series of rotating rolls formed of a chromium alloy arranged transversely in said chamber, and means for rotating the rolls.

2. In a furnace adapted for working temperatures of approximately 1000° to 1900° F., the combination with a heating chamber, of a conveyor comprising a series of rolls of heat resisting material such as a chromium alloy arranged transversely in said chamber, and means for rotating the rolls.

3. In a furnace adapted for working temperatures of approximately 1000° to 1900° F., the combination with a heating chamber, of a conveyor comprising a series of solid rolls formed of a material capable of resisting working temperatures of approxi-

mately 1000° to 1900° F. without distortion and arranged transversely in said chamber, and means for rotating the rolls.

4. In a furnace adapted for working temperatures of approximately 1000° to 1900° F., the combination with a heating chamber, of a conveyor comprising a series of rolls of heat resisting material such as a chromium alloy arranged transversely in said chamber, said rolls being of relatively small diameter and arranged in close proximity to each other so as to convey small articles, and means for rotating the rolls.

5. In a furnace adapted for working temperatures of approximately 1000° to 1900° F., the combination with a heating chamber, of a conveyor comprising a series of solid rolls of heat resisting material such as a chromium alloy arranged transversely in said chamber, said rolls being of relatively small diameter and arranged in close proximity to each other so as to convey small articles, and means for rotating the rolls.

6. In a furnace adapted for working temperatures of approximately 1000° to 1900° F., the combination with a heating chamber of reduced width near the bottom to form a runway, electric heating elements arranged at the upper or wider portion of the heating chamber and between the sides thereof and the sides of the runway, and a conveyor located near the bottom of the runway, the conveyor comprising a series of solid rolls of heat resisting material such as a chromium alloy arranged transversely in the runway, and means for rotating the rolls.

In witness whereof, I have hereunto signed my name.

LEON D. SLADE.
